UNITED STATES PATENT OFFICE.

WILLIAM GRASS, OF WEEHAWKEN, NEW JERSEY, ASSIGNOR TO GRASS PATENTS CORPORATION, OF NEW YORK, N. Y.

METHOD OF LITHOGRAPHIC PRINTING.

Application filed February 10, 1916, Serial No. 77,489. Renewed March 11, 1922. Serial No. 543,090.

To all whom it may concern:

Be it known that I, WILLIAM GRASS, a subject of the Emperor of Germany, residing at Weehawken, in the county of Hudson and State of New Jersey, have invented 5 certain new and useful Improvements in Methods of Lithographic Printing, of which the following is a specification.

The invention relates to a method of lithographic offset printing in which the printing surface is prepared and used in a new and improved way, without the intervention of any individual type or linotype from which an impression is required to be 15 taken in the usual manner.

The invention has for its objects to simplify and improve the printing process, and obtain better results in the distinctness of the printing and in the durability of the devices 20 used, especially of the printing surface and of the master transparency or translucency in which the text or other composition is permanently embodied in a form very convenient for preservation and for reproduction 25 at any time that reprinting is desired.

With such objects in view, as well as other advantages which may be incident to the use of the improvements, the invention consists in the procedure, hereinafter set forth and 30 claimed, with the understanding that the several necessary elements constituting the same may be varied in proportions and arrangement without departing from the nature of the invention.

35 In order to make the invention more clearly understood there are shown in the accompanying drawings means for carrying the same into practical effect, without limiting the improvements, in their useful applications to the particular constructions which, for the purpose of explanation, have been made the subject of illustration. In the said drawings—

Fig. 1 is a front view of a portion of the 45 apparatus, comprising a frame or easel in or on which movable type to be photographed are assembled.

Fig. 2 is a side view of the same, illustrating also a camera for photographing the matter on said easel and showing a hand 50 crank for more readily moving said easel.

Fig. 3 is a horizontal section of said easel on line III—III of Fig. 1 and adding also 55 the said crank.

Fig. 4 is a front view of one of the letters 55 or type.

Fig. 5 is a plan view of the master transparency.

Fig. 6 is a section view on line VI—VI of Fig. 5, the same being in the form of 60 an illustrative diagram.

Fig. 7 is an end view of a lithographic cylinder, having a lithographic grained surface of zinc or its equivalent, and having applied thereto the said master transparency. 65

Fig. 8 is an elevation of the said cylinder having the composition or design to be printed formed in intaglio thereon, in or slightly below the lithographic grain of the surface. 70

Fig. 9 is a vertical sectional view of a portion of the easel, enlarged, with a movable letter or type suspended thereon.

Fig. 10 is a view of a piece of the stripping film. 75

Fig. 11 is a similar view of the stripping dry plate.

Fig. 12 is a sectional view, greatly magnified, showing conventionally a portion of 80 the printing surface or plate.

A indicates an easel or equivalent support, in or on which movable letters or type 1 are to be assembled for the production of text to be printed. Preferably the type supporting face or portion of said easel is vertically movable progressively line by line, from the type setting point upward. The individual type 1 may be slid laterally into the easel from the side, or may be suspended on the surface thereof to form lines of type, and as such lines are formed the front face of the easel is moved upward, such process being continued until the entire composition to be printed, or so much thereof as the easel is capable of containing, has been set in type. 85

The said type are characterized by having their faces white or light-reflecting (Fig. 4), so as to be capable of being clearly photographed, the bases 2 of the individual type around the surfaces of the letters and the entire background of the easel being black or non-reflecting, so that a photograph of the entire composition on the easel will show sharply on the photographic plate or film which is used in the camera. The said camera is shown at B, and is preferably maintained in a constant position a suitable distance from and focused on the face of the 90 100 105

easel, so that when a composition has been set up it may be rapidly photographed.

The faces of the letters on the type are of what may be termed direct reading formation (not reverse reading as in the case of type from which a physical impression is taken) and the composition may be easily read in the ordinary way. Proof reading and correction may continue by a proof reader operating on the type that have been set, while the compositor is still setting up the type at the lower part of the easel. The type will be contained in cases suitably situated at or near the easel within convenient reach, or the type may be assembled mechanically by a linotype apparatus or its equivalent; the present invention however not being confined to any particular means for assembling the type on the easel, and 20 that part of the invention not requiring to be further illustrated herein.

In that form of easel which has been illustrated the type carrying portion consists of an endless carrier comprising belts or chains 25 3 which run upon pulleys rollers, or sprockets 4. The pulleys or roller at the top part of the easel are fixed or mounted on a shaft 5, and those at the bottom of the easel on a shaft 6. A step by step, or line by line, upward movement of the front surface of the easel is produced by hand or by any suitable mechanism for the purpose. On the said chains are mounted horizontal slats or flights 7 which are capable of having the movable 30 type easily and rapidly applied thereto as the setting of the composition to be printed proceeds. The bases 2 of the letters may be provided with hooks 8 adapted to hook over the top edges of the slats (Fig. 9). As 35 the letters pass over the shaft 5 and to the back of the easel they may be automatically discharged by gravity, for distributing into their cases.

The said easel has a surface, on which the 40 arranged type are received as aforesaid, of suitable dimensions to be conveniently focused on a movable film 9 in the camera B. As soon as the composition has been completed in type, which may conveniently be a column or a portion of a column of a newspaper, an exposure is made of the film in the camera, the latter being permanently arranged in proper focus relative to the easel, so that no time is lost in making such exposure. The film is then developed and dried. 45 The film is supplied for each exposure by unwinding from a reel 10, and passes from the camera into a developing trough 11. Until it is developed the film 9 is protected 50 from light except when exposed in the camera. As the subject exposed has white or light-reflecting surfaces against a black or non-reflecting background, no particular care is necessary in the said development of the film, it only being necessary to get a good

black and white negative. It may be here stated that the above described apparatus is capable of producing very clear and perfectly formed letters on the film, the type of white letters which are photographed being 70 several times larger than ordinary type, and of perfect formation; the result being that the film shows letters reduced to the ordinary size desired in a newspaper, but of very perfect formation, distinctness, and 75 alinement.

The film is a contrast stripping film, the emulsion-film face 12 of which can be stripped from the celluloid or equivalent back 13, when the film has been dried, without 80 impairing the integrity of such stripped film (Fig. 10). The latter is then caused to adhere to the surface of a transparent or translucent tissue-paper 14 (Fig. 5), which may be such as is employed in 85 lithography. This paper has a varnished surface composed of linseed oil and resin. A paper known as "photo-phane" is suitable for the purpose.

The above described process of arranging 90 the type and photographing, is continued until sufficient finished film is produced to make a page of a paper. The said columns, or portions of columns, of film are arranged as desired to make up the said page; and 95 they have a natural or direct reading arrangement on the transparency so as to present the letters naturally to the eye. If an illustration is to be inserted in the text, 10 being a picture or photograph of which there is no cut, a negative of the picture is made by a camera and retouched according to the lights which are necessary or desired. The negative is then placed on a stand 10 in front of a camera lens and reflected light is caused to pass through the negative and lens, and through a screen in the camera on to a contrast, stripping dry plate in the camera, 11 on which the picture is produced in dot form. The plate is then developed and dried in the usual photographic way. When dry, the film 15 containing this picture is cut around with a knife and stripped from its plate (Fig. 11) and stuck on said printed transparency 14 at the desired place in a column, or across two or more columns, its arrangement being direct reading and corresponding with the text. A half-tone picture or cut, printed on translucent paper, 12 may be applied on the transparency where desired. The arrangement of the film or parts of film on the transparent sheet being complete, a similar sheet 16 is preliminarily stretched, slightly moistened, as by steaming, and applied on the first sheet 14 of the transparent paper, and rolled down thereon, so that the two transparent sheets form in effect a single sheet with all of the sections of film 12, 15 held in place between them. This complete sheet may be termed 13

a master transparency, and may be used at any time for the production of a lithographic printing plate, and may be indefinitely preserved for the purpose of reprinting at any 5 future time. Before it is put away both of its outside surfaces are rendered non-adhesive by rubbing thereon French chalk or talcum.

Proceeding at this stage of the process 10 with the production of the printing surface, a zinc or aluminum plate 17 having a grained lithographic surface 18 is coated on said surface with a sensitive film 19 (Fig. 7) of fish glue or the equivalent. This film 15 being dry, and having been protected from light, the plate is placed in a printing frame with said prepared transparency 14, 16 back down thereon and is exposed to light, or the transparency may be stuck on as hereafter 20 mentioned. For direct instead of offset printing the transparency would be applied face down on the plate. After said exposure the plate is developed and the unexposed and unhardened parts of the film, 25 which have been protected by the opaque lines or dots of the transparency, are washed or dissolved away by water or the equivalent. The letters are white on the easel, black on the film 12, and spaces representing them are left in the film 19 by said 30 washing. The plate with its remaining hardened film parts is then washed and dried. Preferably before said washing the plate is dyed to make the design clearly 35 visible and enable it to be ascertained whether the design is perfect before proceeding further. The plate 17 is then etched in ferric chloride solution, of preferably about 38 to 43 Baumé, for about two or 40 three minutes, at normal temperature, thereby removing said grain 18 down to the solid part of the plate, and forming in relatively shallow intaglio 20 the lines and dots which are to be printed. The plate is then 45 washed and dipped in a weak hydrochloride bath for about half a minute, to soften the film. Then the hydrochloric solution is 50 washed off and the plate is dried. Lithographic transfer ink or grease 21 (Fig. 12) is then applied or rubbed into the intaglio 55 recesses, and preferably a celluloid or similar varnish 28 is also applied, before, with or after the ink. The application of any material in the intaglio, which makes it receptive of ink, will serve the purpose. The plate is then washed in water and rubbed, as with wool or felt, till all film is removed. The plate is dried and powdered with resin, and the excess of resin is dusted off, and 60 the plate is cleaned and given a surface etch with a solution suitable, according to the material of which the plate is made, to render the normal high parts or parts other than the intaglio, non-receptive of ink when 65 properly damped. The plate is then cleaned

or sponged off with water, and gummed with a thin solution to prevent oxidation and protect the surface of the plate.

The plate is then put in the printing press, in flat form or around a cylinder, the 70 latter for continuous rotary printing.

The intaglio is very shallow. For instance, a plate of about 28/1000 gauge can be repeatedly used, the former designs being 75 etched off, by etching away the high parts by a process analogous to that already described. In both etching processes the back of the plate is or may be protected by a suitable resisting coating. Or the old designs can be removed in any other suitable way. 80

When the intaglio is to be used in cylindrical form, suitable for a rotary newspaper lithographic offset printing machine, the procedure is as follows: The zinc or aluminum plate is or may be produced in the form of a seamless tube 22, which is attached concentrically on a mandrel 23. This plate is evenly coated with a photographic film of fish glue such as is above described, or its equivalent, and the transparency 14, 16 is 85 stuck on it, by an adhesive containing no water, Fig. 7 and exposed to light by rotating the cylinder in front of an arc lamp. The transparency is then stripped from the cylinder and the latter is treated and etched as already described. The adhesive is removed from the back of the transparency by rubbing with benzine; talcum or French chalk is then rubbed on both faces of the transparency and it is laid away until it is 90 required for the preparation of another plate. 95

A relatively coarse and sharp grain on the normal high surface of the intaglio plate is 100 desirable on account of its better water-receiving character and because it adds to the life of the plate, and such grain may be used in the invention described without any consequent roughening of the lines or dots of the design, as would be the case if such grain 105 were used on a planographic plate. The etching herein described as producing an intaglio may also be described as removing the said water-receiving grain, so that the lithographic ink is received wherever the grain has been removed, and its extent is 110 defined and maintained without spreading (so that uniform impressions are produced) by the walls of the remaining grain which surround the places from which the grain has been removed. Less particularity is necessary as to the exact degree of damping, and also as to the quality of the ink, which 115 need not be expensive in order to obtain 120 good impression and color. 125

The film back 13 is preserved and resurfaced with photographic stripping film.

While I have above described the best manner known to me of producing the printing surface, it is to be understood that other 130

methods of producing the suitable printing surface may be employed, and the invention does not exclude the use of a planograph printing plate, although the latter will not 5 give such perfect results and will not be so durable.

It will be understood that the invention may be employed in a process involving the use of two offsetting cylinders simultaneously printing opposite to each other on the opposite sides of a web of paper.

What is claimed is:

1. A process of lithographic printing for newspapers and other purposes, in which 15 a lithographic metal plate is produced by photographing light-reflecting directly reading and individually set up letters having a non-reflecting background, and from the negative so made printing on the plate, 20 and causing said plate to have a normal high ink rejecting surface and surfaces at a slightly lower level, said lower surfaces constituting the design or matter to be printed.

2. A process of lithographic printing for 25 newspapers and other purposes, in which a lithographic metal intaglio plate is produced by photographing light-reflecting letters having a non-reflecting background, moving the said letters, while properly set 30 up, progressively during intervals of photographing and from the negative so made printing on the plate, and causing said plate to have a normal high ink rejecting surface and surfaces at a lower level, said lower 35 surfaces constituting the design or matter to be printed.

3. A process of lithographic printing for newspapers and other purposes, in which a lithographic metal intaglio plate is produced by assembling individual type and 40 photographing the same, and from the negative so made printing on the plate, and causing said plate to have a normal high ink rejecting surface and surfaces at a slightly lower level, said lower surfaces constituting the design or matter to be printed.

4. A process of lithographic printing for newspapers and other purposes, in which a lithographic metal intaglio plate is produced by photographing light-reflecting letters having a non-reflecting background, and from the negative so made printing on the plate by the aid of films carried by a transparency, and causing said plate to have 50 a normal high ink rejecting surface and surfaces at a slightly lower level, said lower surfaces constituting the design or matter to be printed.

5. The herein described process of newspaper and other printing, which consists in 60 making a photographic negative directly from arranged letters, on which negative the letters are light-intercepting on a translucent film or plate; photographing from 65 said negative on a lithographic plate having

a sensitized film on a grained surface; and treating said plate to produce thereon a normal or high surface which is receptive of water and non-receptive of ink when dampened, and ink receiving surfaces at a slightly 70 lower level than said normal surface.

6. The herein described process of newspaper and other printing, which consists in making a photographic negative film directly from arranged letters, on which negative the letters are light-intercepting on the translucent film; applying said film on a transparency, and applying with such text-film other film which is a photographic negative of pictorial matter; photographing from said transparency on a lithographic plate having a sensitized film on a grained surface; and treating and etching 80 said plate.

7. The herein described process of newspaper and other printing, which consists in assembling letters having direct reading white or light-reflecting faces on a non-reflecting background; moving said type as 85 they are assembled to a photographing position; proof-reading and correcting said letters if necessary; photographing an assembled body of said letters on a sensitized film carried by a base film; developing the exposed film; stripping the developed film from said base film; causing said stripped film to adhere on a translucent material; causing another sheet of such translucent material to adhere over said film; printing 90 by light through said composite translucent sheet on to a lithographic plate having a sensitized film on its grained lithographic surface; removing the unexposed and unhardened portions of the plate film from 95 said plate; and etching said plate to produce the letters thereon in intaglio.

8. In newspaper and other printing the process of preparing a photographic negative of matter to be printed, which consists in assembling photographable types successively end to end to produce lines, and guiding the type into position along lines parallel with their faces; making a photographic negative of the text so produced, then moving said text as a whole and causing the 100 photographic field to be occupied by a subsequent portion of said text assembled as above described, and then making another negative of such subsequent portion of text, and so successively and progressively producing the required negatives.

9. In newspaper and other printing the process of preparing a photographic negative of matter to be printed, which consists in assembling photographable types successively end to end to produce lines, and guiding the type into position along lines parallel with their faces; making a photographic negative of the text so produced, then moving said text as a whole and causing the 105

photographic field to be occupied by a subsequent portion of said text assembled as above described, and then making another negative of such subsequent portion of text, and so successively and progressively producing the required negatives, and distributing the type successively as they pass out of the photographic field.

10. The herein described process which consists in assembling photographable type to produce a series of lines of said type, and successively moving suitable numbers of said lines of type into the photographic field, and producing successive photographic negatives of said type, and treating lithographic surfaces with the aid of said negatives for the production of lithographic printing surfaces representing all of said type.

20. 11. The herein described process which consists in assembling photographable type to produce a series of lines of said type, and successively moving suitable numbers of

said lines of type into the photographic field, and producing successive photographic negatives of said type, and treating lithographic surfaces with the aid of said negatives for the production of lithographic printing surfaces representing all of said type, and distributing said type as they pass out of the photographic field.

12. A process of lithographic printing for newspapers and other purposes, in which a lithographic metal plate is produced by photographing light-reflecting designs having a non-reflecting background, and from the negative so made printing on the plate, and causing said plate to have a normal high ink-rejecting surface and having surfaces at a slightly lower level, said lower surfaces constituting the design or matter to be printed.

In testimony whereof I affix my signature.

WILLIAM GRASS.
